UNITED STATES PATENT OFFICE

RICHARD B. AVERY, OF NEW YORK, N. Y., ASSIGNOR OF ONE-HALF TO
GEORGE B. HULME, OF SAME PLACE.

CAR STARTER AND BRAKE.

SPECIFICATION forming part of Letters Patent No. 357,263, dated February 8, 1887.

Application filed May 20, 1886. Serial No. 202,766. (No model.)

To all whom it may concern:

Be it known that I, RICHARD B. AVERY, a citizen of the United States, residing in the city of New York, in the State of New York, have 5 invented certain new and useful Improvements in Car Starters and Brakes; and I hereby declare the following to be a full, clear, and exact description of the same, reference being had to the accompanying drawings, wherein—
10 Figure 1 is a bottom view of a car having devices embodying invention applied thereto. Fig. 2 is a side elevation thereof, showing the arrangement of the gearing for starting the car. Fig. 3 is a similar view of the opposite 15 side, showing the gearing for braking and storing the power. Fig. 4 is a rear, and Fig 5 a front, elevation of the devices. Fig. 6 is a longitudinal central section of the car-bed, shipping-lever, coiled storing-spring, and its casing. Fig. 7 is an enlarged longitudinal section of the storing-spring, its casing, shaft, and bevel-pinions. Fig. 8 is an enlarged detail view of the end of the coiled spring-ratchet. Fig. 9 is an enlarged detail of a portion of one 25 of the bevel-gears, showing the preferred form of teeth. Fig. 10 is a detached plan of the devices, showing how they may be secured to a bed-plate so as to be readily attached to and detached from the bottom of the car.

30 Like letters refer to like parts wherever they occur.

My present invention relates to that class of devices for braking and starting cars wherein the power abstracted in braking is stored in a 35 coiled or equivalent spring, and subsequently utilized by means of a suitable gearing as an auxiliary force in starting the car.

Heretofore the devices employed have been of a more or less complicated character, liable 40 to be deranged by the wear and tear of street-railroad service, and the constant use resulting from frequent stopping and starting of the car have demanded more skill, care, and attention than can be obtained from the average 45 street-car employé, and have been more or less difficult to attach to cars of the ordinary construction.

The main objects of my present invention are to simplify the mechanism, whereby it is 50 not only rendered cheaper and more durable,

but more manageable by unskilled labor; to so construct it as to facilitate its attachment to or removal from the car for repairs, and to so combine the shifting mechanism and gearing as to obtain all the power necessary to bring 55 the mechanism into operation quickly under all conditions incident to the use of such devices.

For said several purposes it consists, generally stated, first, in combining with a car- 60 axle having suitable gear wheels or pinions a shaft having a coiled power-spring, a movable or sliding pinion arranged on the shaft, and a shifting-lever for controlling the sliding pinion, whereby the power exerted in arresting 65 the motion of the axle is stored in the coiled spring; and, secondly, in combining with the first recited devices, or their equivalents, a second pinion fast on the spring-shaft and a third movable pinion controlled by the ship- 70 ping-lever, whereby the power stored in the coiled spring may be exerted on the axle.

It also consists in securing the shifting-lever and the bearings of the spring-shaft to a bed-plate, whereby all the mechanism employed (excepting the pinions on the axle) 75 may be readily attached and removed, and whereby the strength of the connections and support of the devices are greatly enhanced.

There are also certain novel details of construction, all of which will hereinafter more 80 fully appear.

I will now proceed to describe my invention more specifically, so that others skilled in the art to which it appertains may apply the invention.

In the drawings, A indicates the bed or bottom of the car, B the axles, and C' the wheels thereof. At suitable intervals on one of the axles B are placed two bevel-pinions, a b, the first, a, for imparting power to a spring-shaft, and the second, b, for receiving power from the spring-shaft.

Parallel with the car-axle B, and supported in suitable bearings, is a spring-shaft, C, or 90 shaft to which one end of a coiled spring is attached. If desired, the bearings of this shaft C may be on the case D, which incloses the coiled spring.

c indicates a powerful spring, preferably flat, 100

one end of which is attached to the casing D, as at c', or to any other suitable fixed point, while the other is attached to the shaft C, as at c', so that the spring will be coiled and uncoiled by the rotation of shaft C.

15 d is a bevel-pinion, arranged on that end of the shaft C which corresponds with the position of bevel-pinion a of the axle, and said pinion or gear wheel d is adapted to slide longitudinally on the shaft C, into and out of gear with pinion a, but to turn with the shaft C, and this may be accomplished by making the shaft polygonal in cross-section, as at d', by means of a spline or feather, or by any of 20 the many ways known to the skilled mechanic. In the outer face of this pinion or gear wheel d is a coiling groove, d², say one-half or three-quarters of an inch deep, and which makes one, two, three, or more coils, regulated by 25 the number of turns of the axle you desire for coiling the spring c, said groove d² terminating in a deeper slot or pin-hole, d³, (see Fig. 7,) which groove and slot are for the reception of the spring-ratchet I shall next describe.

30 e indicates an arm or post, secured to some fixed point, and extending alongside of the sliding bevel-pinion d, curved or bent at its free end so as to bring the same into the coiling groove d² of the said pinion. Secured to the free end of this arm or post e, and coiled in the groove d² of the pinion d, is a flat spring, f, having at its free end a projection or pin, g, (see Fig. 8,) adapted to enter the pin-hole d³ 35 at the end of groove d² in the face of pinion d. The spring f always remains in groove d², but when the pinion d is moved back from arm or post e the spring f does not touch the bottom of the groove, and consequently the pin g at 40 the end of the spring does not enter the pin-hole d³, so that the pinion d moves freely and independently of the spring f. When, however, the pinion d is moved toward post e, as in throwing it into gear with the bevel-pinion 45 a, the pin g will in due course drop into the pin-hole d³, so that the spring f forms a spring-ratchet for the pinion d, and said ratchet, being in the nature of a spring or friction-band, has many advantages over the ordinary spring 50 dog or pawl and ratchet-wheel.

Secured to the opposite end of shaft C, and substantially in line with the bevel-pinion b of the axle, is a second bevel-pinion, h, for imparting the power from coiled spring c to 55 axle B.

60 E indicates the shipping-lever, having a fixed pivot, as at i, so arranged as to give all the leverage required for operating or shifting the pinions d and h and for holding them up to their work when shifted. At the extremity of the outer or long arm of the lever E is a rack, E', which meshes with the pinion E² on the shaft F of the hand-wheel or brake-rod, by means of which the shipping-lever may be 65 operated. The short arm of shipping-lever E is bent or L-shaped, and terminates in a fork, G, which incloses and controls the pinion d,

so as to shift the position thereby accordingly as the lever or shipper E is moved.

Extending from the shipping-lever E, at a 70 point between its pivot i and the fork G, is an arm or shaft, H, on the outer end of which is journaled a beveled pinion, k, adapted to mesh with the pinion b of the axle, and also with the bevel-pinion h on the end of shaft C when 75 the shipping-lever is properly placed for that purpose.

In order to facilitate the gearing or meshing of the pinions when shifted, the teeth thereof are 80 preferably formed of V-shaped cross-section, substantially as shown in Fig. 9, and this, in conjunction with the coiled power-spring and spring-ratchet, will aid materially in relieving the mechanism from shocks and jars when 85 shifted into and out of gear with the pinions on the axle B.

The shipping-lever E and the casing D, as 90 also the bearings of spring-shaft C and spring-ratchet f, may be attached directly and independently to the bottom of the car, as shown 95 in Fig. 1; but as this would require the relative adjustment of the several parts wherever they were attached or replaced, and would multiply the number of fastenings at different points on the car-bottom, with consequent loss 100 of strength in the individual fastenings, I prefer to secure or mount all the above-recited parts on a single bed-plate, (or suspension-plate,) P, as shown in Fig. 10, as thereby the connection between the several parts and the 105 plate P can be made at the shops, and can be more thoroughly and easily accomplished, while the plate P can be more readily and securely bolted to the bottom of the car than could the individual elements composing the 110 devices.

The devices being of the general character hereinbefore described will operate as follows: When the shipping-lever E stands in position to keep the pinion d out of gear with a, and k out of gear with b and h, the devices will be 115 inoperative; but when it is desired to arrest the motion of the car or apply the brakes thereto, the shipping-lever E is moved by means of shaft F and pinion E², which meshes in the rack E' on the end of lever E, so as to cause bevel-pinion d of the spring-shaft C to mesh with bevel-pinion a of axle B. This movement of sliding bevel-pinion d forces the spring-ratchet f to the bottom of groove d² in 120 the face of pinion d, and the pin g enters pin-hole d³. The motion of axle B is communicated to spring-shaft C, winding up spring c and arresting the motion of axle B by a gradual spring or yielding resistance, which precludes sudden jars or shocks. When the 125 spring-shaft has given spring c the number of coils corresponding to the number of coils of spring-ratchet f, said ratchet comes into play and prevents the uncoiling of spring c so long as the pinions a and d are in mesh and the 130 spring-ratchet f is in the bottom of groove d. When, however, it is desired to employ the power stored in spring c for starting the car,

the shipping-lever E is moved by the devices before specified in the reverse direction until the pinion *k* meshes with the pinion *h* on the spring-shaft C and the pinion *b* on the axle B, 5 which movement of the lever E draws pinion *d* away from post *e*, lifts spring *f* partly out of groove *d*², so that pin *g* is drawn out of pin-hole *d*², thus freeing the pinion *d* of shaft C and allowing power-spring *c* to uncoil and apply its power through shaft C and pinions *h k* 10 *b* to the axle B as an auxiliary in starting the car.

I am aware that a coiled-spring accumulator arranged on a spring-shaft having a sliding bearing and having pinions which mesh with pinions on the axle has heretofore been devised, and do not herein claim such a combination, as the tendency thereof is to cause the 15 brakes to be applied by the action of the spring sliding bearing of the shaft, unless the movement of the shaft is constantly restricted by the brake-chain.

Having thus pointed out the construction, operation, and advantages of my invention, 20 what I claim, and desire to secure by Letters Patent, is—

1. In a car brake and starter, the combination, with a car-axle having a pinion thereon, of a spring-shaft having a sliding pinion, a 25 shipping-lever for controlling the sliding pinion, and a coiled power-spring, substantially as and for the purposes specified.

2. In a car brake and starter, the combination, with an axle having a pinion thereon, of 30 a spring shaft, a power-spring, a sliding pinion having a coiling groove in its face, and a coil-spring ratchet, substantially as and for the purposes specified.

3. The combination, with a car-axle having a pinion thereon, of a spring-shaft having a power-spring connected thereto and a pinion thereon, a pinion adapted to mesh with the pinion of the axle and with that on the spring-shaft, and a shipping-lever adapted to move the last-named pinion into and out of gear, 45 substantially as and for the purposes specified.

4. In a car brake and starter, the combination of an axle having two pinions thereon, a spring-shaft parallel therewith and having a fixed and a sliding pinion, a coiled spring attached to the spring-shaft, a shipping-lever having a fork to control the sliding pinion of the spring-shaft, and a pinion-arm and a pinion, substantially as and for the purposes specified.

5. In a car brake and starter, the combination, with the shipping-lever, spring-shaft and its bearings, and a power-spring, of a bed-plate whereon said parts are secured so as to preserve the connection and relation of the several parts when detached from the car-bed, 55 substantially as and for the purposes specified.

6. In a car brake and starter, the combination, with the movable gearing, of a pivoted lever having a rack, and a pinion for operating the said lever, substantially as and for the purposes specified.

In testimony whereof I affix my signature, in presence of two witnesses, this 19th day of May, 1886.

RICHARD B. AVERY.
